PARASITIC OSCILLATION SUPPRESSOR

Filed May 15, 1941

UNITED STATES PATENT OFFICE

2,290,659

PARASITIC OSCILLATION SUPPRESSOR

Donald E. Watts, Schenectady, N. Y., assignor to
General Electric Company, a corporation of
New York

Application May 15, 1941, Serial No. 393,597

5 Claims. (Cl. 179—171)

This invention relates to electron discharge amplifiers, and more particularly to means for damping parasitic oscillations in such amplifiers.

Electron discharge amplifiers, and particularly those which operate at high power levels and thereby necessarily have conductors of substantial size and length constituting various portions of the amplifier circuit, are frequently subject to self oscillation at undesired frequencies different from the resonant frequency of the amplifier circuit. Such self oscillation, usually termed parasitic oscillation, is caused by stray capacities and the like acting in resonance with circuit inductances including the inductance presented by circuit conductors due to their physical length. It is an object of my invention to provide improved means for suppressing such undesired oscillation.

In such amplifiers neutralizing circuits are provided for preventing self oscillation of the amplifier. Parasitic oscillations occur because such neutralizing circuits do not perform properly at certain frequencies, at which parasitic oscillations occur. It is a further object of my invention to provide simplified and improved parasitic oscillation suppressing means placed in such neutralizing circuits of an amplifier in such position that most parasitic oscillations are effectively suppressed with minimum loss of driving power supplied to the amplifier.

It is another object of my invention to provide other parasitic oscillation suppressing means cooperating with such means in the neutralizing circuit for effectively suppressing parasitic oscillations not affected by the means in the neutralizing circuit.

The features of my invention which I believe to be novel are set forth with particularity in the appended claims. My invention itself, both as to its organization and manner of operation, together with further objects and advantages thereof may best be understood by reference to the following description taken in connection with the accompanying drawing in which the single figure illustrates an amplifier circuit embodying my invention.

In the drawing an inductance 10, excited from a source of high frequency potential, not shown, is tuned to resonance at such high frequency by four condensers 11, 12, 13, and 14, connected serially in that order between the terminals of the inductance 10. A point between condensers 12 and 13 is connected to ground through a resistance 50. A pair of electron discharge amplifier devices 15 and 16 are excited from the tuned circuit 10, 11, 12, 13, 14, and transmit amplified

oscillations to a tuned output circuit including an inductance 17 in parallel to two serially connected condensers 18 and 19. A point between these two condensers 18 and 19 is grounded.

Exciting connections for the device 15 are provided from a point between condensers 11 and 12 through a resistance 20, shunted by an inductive conductor 21, to the control electrode 22 of the device 15. Similar exciting connections are provided for the discharge device 16 from a point between the condensers 13 and 14 through a resistance 23, shunted by an inductive conductor 24, to the control electrode 25 of the device 16.

In order to transmit unidirectional current from the control electrodes 22 and 25 to ground, points between the condensers 11 and 12 and the condensers 13 and 14 are connected respectively through a series combination of inductance 26 and resistance 27 and a similar series combination of inductance 28 and resistance 29 to a point maintained at a suitable negative bias potential with respect to ground. The negative bias potential is supplied to such point through a resistance 30 from the negative terminal of a source 31 of potential, the positive potential of the source 31 being grounded. A condenser 32 is connected from the common point of resistances 27 and 29 to ground for bypassing high frequency current from such point to the cathodes of devices 15 and 16.

The filamentary cathodes 33 and 34 of the devices 15 and 16 are respectively connected serially with the secondaries 35 and 36 of a filament heating transformer 37, energized with alternating cathode heating potential from a source, not shown. In order to transmit unidirectional currents from the cathodes 33 and 34 to ground, the center tap of the secondaries 35 and 36 of the transformer 37 are grounded. In order to transmit high frequency current from the cathodes 33 and 34 to ground, the four cathode terminals of the devices 15 and 16 are respectively connected to ground through four condensers 38, 39, 40, and 41.

Anode current for the devices 15 and 16 flows through connections extending from the respective anodes 42 and 43 of such devices through inductance 17 and an inductance 44, which is shunted by a series resonant circuit including an inductance 45 and a condenser 46 which is connected between an intermediate tap of inductance 17 and the positive terminal of a source 47 of potential, the negative terminal of which source is grounded to the cathodes of the dis-

charge devices. A point between the condensers 18 and 19 is also connected to ground.

In order to provide neutralization for the amplifier, a condenser 48 is connected from a point between inductance 26 and resistance 20 to the anode 43 of device 16, and a second condenser 49 is connected from a point between inductance 28 and resistance 23 to the anode 42 of device 15.

Of course, it should be understood that resistances 20 and 23, and the associated conductors 21 and 24, should be mounted as close to the connections to the corresponding control electrodes as possible. Also, the connections from condensers 48 and 49 to the corresponding resistances 20 and 23 should be made as close to the resistances as possible.

In the usual amplifier, which does not have the resistances 20 and 23 and the inductive conductors 21 and 24, parasitic oscillations generally occur because the neutralizing circuit is not a perfectly balanced bridge circuit at all frequencies by reason of the fact that the conductors in the bridge circuit have inductance due to their physical length. By placing the resistances 20 and 23, shunted respectively by the inductive conductors 21 and 24, in the circuit common to the grid cathode circuit and the neutralizing circuit of each discharge device, it is possible to suppress most parasitic oscillations which can arise in the amplifier, by producing critical damping in the amplifier circuits in which such oscillations arise, that is, by producing just enough damping in the circuits of the amplifier to prevent oscillations therein, while suitably proportioning the values of the resistances, and the inductance of the conductors in shunt thereto, to require minimum drive voltage for the amplifier.

So far as is known, the correct values for the resistances 20 and 23 and the inductive conductors 21 and 24 cannot be predetermined for a given amplifier. The values are most easily determined by trial, and may conveniently be determined by the following procedure. The resistances 20 and 23 are each given a value in the order of 20 to 100 ohms, the value preferably being 100 ohms in order to avoid any danger of overheating the resistor. Each resistance is preferably a short non-inductive resistor, such as may be formed by a stick of carbon. Each inductive conductor 21 and 24 is preferably formed by a conducting holder for the accompanying resistance. This holder may have, for example, as is shown in the drawing, an elongated U-shaped form, between the ends of which the resistance is supported. For the first trial it is preferred to make this conductor as short and straight as possible.

The amplifier is then excited with a driving voltage of the proper operating frequency, which is the same as the resonant frequencies of the tuned circuits 10, 11, 12, 13, 14, and 17, 18, 19. This driving voltage is adjusted to the minimum value at which efficient operation of the discharge devices 5 and 16 may be attained. If parasitic oscillations appear after such adjustment of the resistances 20 and 23 and conductors 21 and 24, further adjustments must be made. The first step in such further adjustments is to increase the length, and correspondingly the inductance, of the conductors 21 and 24. By increasing the inductances of these conductors in successive steps a point can be reached at which parasitic oscillations cease. If at such adjustment the amplifier provides its rated output with the above-mentioned minimum driving voltage, the

adjustment of the conductors 21 and 24 is satisfactory. If, however, a substantially increased driving voltage is necessary under such conditions of adjustment to maintain rated output for the amplifier still further adjustment must be made. This further adjustment involves decreasing the inductance values of the conductors 21 and 24 in order to obtain sufficient excitation for the amplifier, with the minimum driving voltage mentioned above.

Such further adjustment comprises decreasing the value of resistances 20 and 23, and repeating the trials with successively increasing values of inductance for the conductors 21 and 24, until a point is reached at which parasitic oscillations cease. If rated output for the amplifier is then obtained with the minimum driving voltage, the adjustment is satisfactory. If not, the value of resistance 20 and 23 is further decreased in steps, the inductances 21 and 24 being properly adjusted at each step, until a point is reached at which parasitic oscillations do not exist and the amplifier operates efficiently at its rated output with minimum driving voltage.

During the above described process of adjustment of the resistances 20 and 23 and conductors 21 and 24, the heat dissipation required of the resistances 20 and 23 may exceed the rated heat dissipation thereof. If the rated heat dissipation of these resistances 20 and 23 is exceeded, the final adjustment to obtain efficient operation of the amplifier is unobtainable with resistances of such rating. Either single resistances of higher rating without substantially greater inductance may be utilized, or preferably two separate resistances of the same heat dissipation rating may be connected in parallel to each other to form each of the resistances 20 and 23. The use of a plurality of such resistances connected in parallel not only multiplies the heat dissipation of the resistance element formed thereby, but also decreases the inductance of the resistance element, thereby decreasing the inductance necessary in the conductors 21 and 24 and correspondingly making it easier to utilize the minimum driving voltage to obtain rated output for the amplifier.

After such adjustments have been completed, it may be found that parasitic oscillations still exist which cannot be suppressed by such means. If such be the case, the resistances 21, 29 and 50, or the series resonant circuit 45, 46 may be utilized to suppress the remaining parasitic oscillations.

Such unsuppressed parasitic oscillations may be caused by the discharge devices 15 and 16 operating either in push-pull, or balanced relation, or in parallel with each other. If the parasitic oscillations appear in substantially constant intensity all along the length of the inductance 17, they are caused by the devices 15 and 16 operating in parallel. If, however, the parasitic oscillations are most intense at the ends 65 of the inductance 17, and are a minimum at its center tap, the devices 15 and 16 are operating in push-pull to produce such oscillations.

If it be found that the parasitic oscillations are caused by the devices 15 and 16 operating in parallel, the frequency of the parasitic oscillations so caused is determined, and the tuned circuit 45, 46 is made series resonant at such frequency. The center tap of the inductance 17 is therefore effectively connected to ground for high frequency current at such frequency, and con-

sequently parasitic oscillations of such frequency, caused by parallel operation of the devices 15 and 16, cannot occur.

If the unsuppressed parasitic oscillations are caused by push-pull, or balanced, operation of the devices 15 and 16, the resistances 27 and 29, connected in series with the inductances 26 and 28, preferably at the grounded ends thereof, and the resistance 50, may be adjusted in value until such parasitic oscillations cease. As is the case with the resistances 20 and 23 and the inductive conductors 21 and 24, the proper values for the resistances 27 and 29 cannot be predetermined, so far as is now known. It is preferred to determine the values of the resistances 27 and 29 by trying initially resistances of some small value, such, for example, as 50 ohms, and increasing the value thereof in small steps until such parasitic oscillations cease. It has been found in typical amplifiers that resistances 27 and 29 may have values, for example, of the order of 300 ohms, while resistance 50 may be of the order of 20 ohms. Such typical amplifiers were operated at frequencies of about four megacycles, and parasitic oscillations of the order of forty megacycles were suppressed by the use of applicant's teachings.

While I have shown and described a particular embodiment of my invention, it will be obvious to those skilled in the art that changes and modifications may be made without departing from my invention in its broader aspects, and I, therefore, aim in the appended claims to cover all such changes and modifications as fall within the true spirit and scope of my invention.

What I claim as new and desire to secure by Letters Patent of the United States is:

1. In combination, an electron discharge device having an anode, a cathode, and a control electrode, an input circuit extending between said cathode and control electrode, an output circuit including a source of operating potential and a conductive impedance extending between said anode and cathode, said circuits being arranged for operation at a predetermined frequency and having undesired feedback therebetween which tends to produce self-oscillation at another frequency through said device, and means for by-passing currents of said other frequency around said conductive impedance through an impedance sufficiently low that said self-oscillation is suppressed at said other frequency, said conductive impedance and said by-passing means having substantial impedance at said predetermined frequency.

2. In combination, an electron discharge device having an anode, a cathode, and a control electrode, an input circuit extending between said cathode and control electrode, an output circuit including a source of operating potential and a conductive impedance extending between said anode and cathode, said circuits being arranged for operation at a predetermined frequen-

cy and having undesired feedback therebetween which tends to produce self-oscillation at another frequency through said device, and means comprising a circuit series resonant at said other frequency for by-passing currents of said other frequency around said conductive impedance.

3. In combination, an electron discharge device having an anode, a cathode, and a control electrode, an input circuit extending between said cathode and control electrode, an output circuit extending between said cathode and anode, means for applying a voltage from said anode through a portion of said output circuit to said control electrode in such phase as to suppress self-oscillation of said device at an undesired frequency, said means being ineffective to suppress such self-oscillation at another frequency, and means in the remaining portion of said output circuit to reduce the impedance thereof at said other frequency to a value sufficiently low that self-oscillation at said other frequency is suppressed.

4. An amplifier comprising a pair of electron discharge devices each having an anode, a cathode, and a control electrode, input and output circuits respectively connecting said control electrodes and said anodes in balanced relation with respect to said cathodes, said output circuit having separate branches extending to each of said anodes and a common branch including a source of operating potential, means for applying a voltage from said output circuit to each of said control electrodes through a corresponding portion of said input circuit in such phase as to suppress self-oscillation of said amplifier, said means being ineffective to suppress such self-oscillation at undesired frequencies, damping means in each of said portions of said input circuit to produce critical damping in the circuits of said amplifier for one of said other frequencies, and means to reduce the impedance of said common branch of said output circuit at another of said other frequencies to a value so low that self-oscillation of said devices at such other frequency is suppressed.

5. A balanced amplifier having an output circuit and two input terminals, and a grounded terminal of intermediate potential, a tuned circuit connected between said input terminals and having an intermediate potential point, a resistance connected from said point to said grounded terminal, said amplifier having a tendency to self-oscillation by reason of feed-back from said output circuit to said input terminals at a certain frequency, and an impedance including a resistance connected from each of said input terminals to said grounded terminal, said three resistances being of such size and so related to each other as to produce critical damping in the circuits of said amplifier at said certain frequency, thereby to suppress such self-oscillation.

DONALD E. WATTS.
